WIND-DRIVEN ROTARY BUBBLE BLOWER

Alexander Clark, Hendersonville, N.C.

Application December 24, 1956, Serial No. 44,315

Term of patent 14 years

(Cl. D34—15)

FIG. 1.

FIG. 2.

FIG. 3.

FIG. 4.

FIG. 5.

Fig. 1 is a front perspective view of a wind-driven rotary bubble blower, showing my new design;
Fig. 2 is a side elevational view;
Fig. 3 is a top plan view;
Fig. 4 is a front elevational view; and
Fig. 5 is a rear elevational view thereof.
A portion of the drawing figures is diagonally lined to indicate transparency.

I claim:

The ornamental design for a wind-driven rotary bubble blower, substantially as shown and described.
